(57) **CLAIM**

The ornamental design for a dual handle electric hair dryer, as shown and described.

DESCRIPTION

FIG. 1 is a perspective view of the dual handle electric hair dryer of my new design;

FIG. 2 is a side elevational view of the dual handle electric hair dryer of FIG. 1, the opposite side being a mirror image of the side shown;

FIG. 3 is a top plan view of the dual handle electric hair dryer of FIG. 1;

FIG. 4 is a front elevational view of the dual handle electric hair dryer of FIG. 1;

FIG. 5 is a rear elevational view of the dual handle electric hair dryer of FIG. 1; and,

FIG. 6 is a bottom plan view of the dual handle electric hair dryer of FIG. 1.

The broken lines in the drawing are for illustrative purposes only and form no part of the claimed design.
